UNITED STATES PATENT OFFICE.

EMMETT W. STULL, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

SYSTEM OF CONTROL.

No. 910,604.

Specification of Letters Patent.

Patented Jan. 26, 1909.

Application filed June 8, 1906. Serial No. 320,755.

To all whom it may concern:

Be it known that I, EMMETT W. STULL, a citizen of the United States, residing at Norwood, in the county of Hamilton and State 5 of Ohio, have invented certain new and useful Improvements in Systems of Control, of which the following is a full, clear, and exact specification.

My invention relates to controllers for electric motors and particularly to series-parallel controllers for electric railway motors.

One of the objects of my invention is to provide an arrangement whereby the motors may be connected in series, in multiple series, 15 and in full multiple in the different positions of the controller, thereby allowing the greatest efficiency of the motors under different conditions to be obtained.

A further object of my invention is to so 20 arrange the coöperating contacts of the controller that sparking or destructive arcing shall be reduced to a minimum.

Another object of my invention is to prevent improper handling of the controlling 25 drum by providing a novel interlocking arrangement between the controlling drum and reversing switch so that the latter can be moved only when the former is in a predetermined or "off" position.

30 My invention in one of its aspects consists of a controller for a plurality of electric motors, having coöperating contact segments and contact fingers so connected and arranged that whenever circuit is broken by 35 the operation of the controller there are at least twice as many places where circuit is broken as there are motors to be controlled.

In another aspect my invention comprises 40 the combination of the plurality of electric motors, and a controller therefor consisting of a single drum having contacts so connected and arranged that the motors are first connected in full series, then in multiple series and finally in full multiple.

45 In a more specific aspect my invention consists in the combination of two groups of electric motors, a regulating resistance and a controller having contacts so connected and arranged that as the controller is 50 operated, the different groups of motors and the resistance are first connected in series and the resistance gradually cut out, and then the groups of motors are connected in parallel to each other with each group in

series with half of the resistance and these 55 halves of the resistance gradually cut out.

In a more specific aspect my invention comprises the combination of four electric motors, a controller consisting of a drum so connected and arranged that the motors are 60 first connected in series, then in multiple series and finally in full multiple, and a resistance which is in circuit with the motors at the beginning of the first step and half of which is in circuit with each pair of motors 65 at the beginning of each other step, the resistance during each step being gradually cut out.

From another point of view my invention comprises the combination of a controlling 70 drum, a reversing switch, and two interlocking arms pivoted to swing in different planes and arranged to interlock to prevent movement of the reversing switch only when the controlling drum is out of "off" position. 75

More specifically considered my invention comprises the combination of a controlling drum, a reversing switch, two arms pivoted to swing in substantially horizontal and vertical planes respectively, and means carried 80 by the shaft of the controlling drum which when the drum is in an "on" position supports the vertically swinging arm in the plane in which the other arm swings, to prevent movement of the reversing switch, and 85 when the controlling drum is in "off" position moves the vertically swinging arm out of the plane in which the other arm swings, to permit movement of the reversing switch.

Other features of my invention will more 90 clearly appear in the following specification and the accompanying drawings and will be specifically pointed out in the appended claims.

Figure 1 is a front elevation of the upper 95 part of my improved controller with the front part of the casing removed and some of the parts in section. Fig. 2 is a plan view on a larger scale of the same controller showing the operation of the interlocking mechanism. 100 Fig. 3 is a diagram of the connections, including the main controlling drum shown in development and arranged according to my invention, the reversing switch and certain other parts being omitted from this diagram 105 for the sake of simplicity; and, Figs. 4 to 10 inclusive show simple connection diagrams for various controller positions.

In the drawings A is a controller casing in which are mounted, as in bearings B' and C', the main controlling drum B and the reversing switch C. These may be of any desired 5 construction and the reversing switch may be connected in any desired manner, the connections of the main controlling drum being shown in Fig. 3. This drum and the reversing switch are operated by the usual handles 10 b and c.

On the shaft of the controlling drum is a notch plate or star wheel D with which the usual spring pressed pawl roller 5 coacts. Extending upwardly from the notch plate D 15 is a ring 6, the upper surface of which is shaped to form a cam 7. An arm 8, pivoted to swing in a vertical plane and drawn downward by gravity which may be assisted by a spring 9, has an extension 10 from its free 20 end which rides on the upper surface of ring 6 and cam 7. When the controlling drum B is in any of its "on" positions the arm 8 is in the horizontal plane in which it is shown in Fig. 1, but when the controlling drum is in 25 its "off" position the arm 8 is raised out of this plane.

Swinging in the horizontal plane in which the arm 8 is shown in Fig. 1 is a second arm 11 drawn by a spring 12 into engagement 30 with a notch plate E on the shaft of the reversing switch C. When arm 8 is in the position shown in Fig. 1, as is the case when the controlling drum is in any of its "on" positions, the arm 11 and consequently the reversing switch C are locked against movement because the arm 8 is in the path of movement of the arm 11, the shoulder 13 of said arm 8 bearing against the side of ring 6. At this time it is impossible, therefore, to 40 move the reversing switch from whatever position it may occupy into any other position, thus preventing reversal or starting of the motors with the main drum in any "on" position. When the controller is in "off" 45 position and the arm 8 is lifted by the cam 7, the path of the arm 11 is open and the reversing switch may be moved as desired.

Referring to Fig. 3, the motors 1, 2, 3 and 4 are connected all in series in positions 1 to 50 5 of the controller, the resistance 14 being connected in series with these motors when the controller is in position 1 and being gradually cut out as the controller is moved to position 5. When the controller is moved to position 6 the group of motors 1 and 2 and the lower half of the resistance 14 are connected in series and the groups of motors 3 and 4 and the upper half of resistance 14 connected in a parallel series circuit. The 55 motors remain in this multiple series connection as the controller is moved to positions 7 and 8, the parts of the resistance which are in the two circuits being gradually and simultaneously cut out as the controller 60 moves from positions 6 to 8. When the con-

troller is moved into position 9, the four motors are connected in full parallel, the lower half of resistance 14 being connected in series with the pair of motors 1 and 2, and the upper half of resistance 14 being connected in 70 series with the pair of motors 3 and 4. These two halves of the resistance are gradually and simultaneously cut out as the controller is moved into positions 10 and 11, the 75 connections of the motors otherwise remaining the same. As the controller passes from positions 5 to 6 and from 8 to 9 the circuit is interrupted, such interruption taking place at a plurality of points, there being at least two points of interruption for each motor. 80 In both cases previous to the actual interruption of the circuit, the resistance 14 is reinserted in the circuit. A similar interruption of the circuit takes place as the controller is moved backward from positions 9 to 8 and 85 from 6 to 5, and also as the controller is moved from position 1 to "off" position. By this multiplicity of breaks the sparking which occurs at any one contact is greatly diminished. As the controller is moved 90 from position 9 to position 8, the circuit is broken at no less than eleven places.

By having the three steps or sets of positions on the controller, i. e., the full series, multiple series and the full multiple, a very 95 efficient regulation of the motors can be obtained. This arrangement is also advantageous for cars which travel in both city and country districts. In such case the controller positions 9, 10, and 11 should be used 100 only in the country districts to obtain a higher speed than is allowed in the city districts.

It is obvious that many equivalents of the various parts shown and described may be 105 used without departing from the spirit and scope of my invention, and therefore I do not wish to be limited to the exact structure which is here shown and described as what I now consider to be the preferred embodiment 110 of my invention, but I aim to set up in my claims, the broad and novel features invented by me.

What I claim as new and desire to secure by Letters Patent is:—

1. In combination, a plurality of electric motors, a regulating resistance, and a controller comprising a single drum, and arranged to vary said resistance and to connect 120 said motors in their entirety in series, in multiple series, and in full multiple.

2. In combination, two groups of electric motors, a regulating resistance, and a controller having contacts so connected and arranged that as the controller is operated the 125 different groups of motors and the resistance are first connected in series with the motors of each group in series, and the resistance gradually cut out, then the groups of motors connected in parallel with each other with 130

- the motors of each group in series and each group in series with half the resistance, and these halves of the resistances gradually cut out, and then the groups of motors connected 5 in parallel with each other with the motors of each group in parallel and each group in series with half the resistance, and these halves of the resistances gradually cut out.
3. In combination, two groups of electric 10 motors, a regulating resistance, and a controller having contacts so connected and arranged that as the controller is operated the different groups of motors and the resistance are first connected in series with the motors 15 of each group in series, and the resistance gradually cut out, then the groups of motors connected in parallel with each other with the motors of each group in series and each group in series with half the resistance, and 20 these halves of the resistances gradually cut out simultaneously, and then the groups of motors connected in parallel and each group in series with half the resistance, and these halves of the resistances gradually cut out 25 simultaneously.
4. In combination, four series electric motors, and a controller consisting of a single drum arranged to connect said motors in full series and in full parallel and to vary a resistance in circuit with said motors in their entirety.
5. In combination, four electric motors, and a controller consisting of a single drum so connected and arranged that it connects 35 the motors first in full series, then in multiple series, and finally in full multiple, and a resistance which is arranged to be connected in the circuit at the beginning of each step and to be gradually cut out by said drum.
- 40 6. In combination, four electric motors, and a controller consisting of a single drum so connected and arranged that it connects the motors first in full series, then in multiple series, and finally in full multiple, and a resistance which is in circuit with the motors at the beginning of the first step and half of which is in circuit with each group of two motors at the beginning of each other step, which resistance during each step is gradually cut out.
- 45 7. In combination, four electric motors, a regulating resistance, and a controller consisting of a single drum having contacts so connected and arranged that the motors and 55 the resistance are connected all in series, and the resistance gradually cut out, and later the motors are connected all in parallel with each pair of motors in series with half said resistance, and said resistance gradually cut out.
8. In combination, a plurality of motors and a controller consisting of a single drum having contacts so connected and arranged that the motors are first connected in full series, then in multiple series, and finally in full 60
- multiple, and a resistance which is arranged to be connected in the circuit at the beginning of each step and to be gradually cut out by said drum.
9. In combination, a plurality of motors, 70 and a controller consisting of a single drum having contacts so connected and arranged that the motors are first connected in full series, then in multiple series, and finally in full multiple, and a resistance which is in circuit with the motors at the beginning of the first step, and part of which is in circuit with each parallel group of motors at the beginning of each other step, which resistance during each 75 step is gradually cut out.
10. In combination, a controlling drum, a reversing switch, two interlocking arms pivoted to swing in non-parallel planes, and arranged to interlock to prevent movement of the reversing switch only when the controlling 80 drum is out of "off" position.
11. A controller comprising a controlling drum, a reversing switch, arms pivoted to swing in different planes, a notch plate on the shaft of the reversing switch with which one of said arms engages, and means for supporting the second arm in the path of the first arm to prevent movement of the reversing switch when the drum is out of "off" 85 position and to move it out of such path to allow movement of said arm when the drum is in "off" position.
12. A controller for electric motors comprising a controlling drum, a cam-bearing ring carried by the shaft of the drum, an 100 arm engaging said ring and movable by said cam, a reversing switch, a notch plate therefore, a second arm pivoted to swing in a plane at an angle with the plane in which said first arm swings and engaging said notch plate, 105 the arms and cam being so arranged that when the controller is not in "off" position, the first arm is in the path of the second to lock the reversing switch against movement and when the controller is in "off" position 110 the first arm is moved out of the path of said second arm to allow movement of the reversing switch.
13. In combination, a controlling drum, a reversing switch, two interlocking arms pivoted to swing in planes at an angle to each other, a notch plate on the reversing switch which one of said arms engages, the arms being arranged to interlock and prevent movement of said reversing switch only when the 115 controller drum is out of "off" position.
14. A controller comprising a controller drum, a reversing switch, two arms pivoted to swing in planes at an angle to each other, and arranged to be in substantially the same 120 plane to prevent movement of the reversing switch when the controlling drum is in any "on" position, but to be out of the same plane to permit movement of the reversing switch when the drum is in "off" position.

15. A controller comprising a controlling drum, a reversing switch, two arms pivoted to swing in substantially horizontal and vertical planes respectively, and means carried by the shaft of the controlling drum, which, when the drum is in an "on" position, supports the vertically swinging arm in the plane in which the other arm swings to prevent movement of the reversing switch, and when 10 the controlling drum is in "off" position moves the vertically swinging arm out of the plane in which the other arm swings, to permit movement of the reversing switch.
16. In a controller, a controlling drum, a reversing switch, a notch plate on the reversing switch shaft, a horizontally swinging spring-pressed arm coacting with the notch plate, a vertically swinging arm, a cam-bearing ring carried by the drum shaft, and sup- 15 porting the vertically swinging arm in the path of the other arm when the controller is 20 in any "on" position, to prevent movement

of the reversing switch, the vertically swinging arm being moved by the cam out of such path when the controller drum is in "off" 25 position.

17. In combination, two electric switches, two arms swinging in vertical and horizontal planes respectively, and means operative with one of the switches for supporting the vertically swinging arm in the path of the other arm when said first switch is in certain predetermined positions, thereby preventing movement of the horizontally swinging arm and the second switch, and for moving said vertically swinging arm out of the path of the other arm when the first switch is in another predetermined position.

In testimony whereof I affix my signature, in the presence of two witnesses.

EMMETT W. STULL.
